UNITED STATES PATENT OFFICE

90,914

DESIGN FOR AN EMBROIDERED TEXTILE FABRIC

Max U. Juestrich, Ridgefield, N. J., assignor to
The American Fabrics Company, Bridgeport,
Conn., a corporation of Connecticut

Application December 27, 1932. Serial No. 46,634

Term of patent 3½ years

To all whom it may concern:

Be it known that I, MAX U. JUESTRICH, a citizen of the United States, residing at Ridgefield, county of Bergen and State of New Jersey, have invented a new, original, and ornamental Design for Embroidered Textile Fabric, of which the following is a specification, reference being had to the accompanying drawing, forming part thereof.

Figure 1 is a plan view of a piece of textile fabric embodying my new design; and

Figure 2 is a view in section taken on the line 2—2 of Fig. 1.

The embroidered textile fabric shown in the

drawing comprises a suitable piece of cloth 10 on which I embroidered broad bands of stitching 11 and 12 which intersect one another substantially at right angles and also with narrower intersecting bands of stitching 13 and 14. A raised pattern is formed by the stitching on each face of the cloth as clearly shown in Fig. 2. The hatching shown at 15 in Fig. 1 represents the weave of the cloth 10.

I claim:

The ornamental design for embroidered textile fabric substantially as shown and described.

MAX U. JUESTRICH.
